GAME BOARD

Charles J. Schultz, P.O. Box 5324,
Reno, Nev. 89503

Filed Aug. 10, 1967, Ser. No. 8,224

Term of patent 14 years

(Cl. D34—5)

The figure is a plan view of a game board showing my new design. The game board is of conventional thickness.

I claim:

The ornamental design for a game board, as shown and described.
